G. D. POGUE,
WATER COOLED PISTON,
APPLICATION FILED JAN. 7, 1915.

1,180,878.

Patented Apr. 25, 1916

UNITED STATES PATENT OFFICE.

GEORGE D. POGUE, OF ST. LOUIS, MISSOURI.

WATER-COOLED PISTON.

1,180,878.

Specification of Letters Patent. Patented Apr. 25, 1916.

Application filed January 7, 1915. Serial No. 966.

To all whom it may concern:

Be it known that I, GEORGE D. POGUE, a citizen of the United States, residing at St. Louis, Missouri, have invented a certain new and useful Improvement in Water-Cooled Pistons, of which the following is a full, clear, and exact description, such as will enable others skilled in the art to which it applies to make and use the same.

10 This invention relates to water-cooled pistons for internal combustion engines and other machines, and has for its main object to provide a water-cooled piston in which the means that conducts the cooling water to 15 and from the water chamber in the piston is so designed that there is no liability of water leaking out of same into the crank case or other part of the engine that contains the lubricating oil, thus impairing the 20 efficiency of the oil.

Another object is to provide a structure of the character mentioned that comprises an extensible water conduit which is so designed that if a leak develops in same this 25 fact will be made known to the operator in charge of the engine.

Another object is to provide a structure of the character described which is so designed that the leak in the conduit can be 30 stopped by manipulating a device accessible from the outside of the engine, which device can be actuated even while the engine is in operation. And still another object is to provide a piston that comprises a water 35 space which is completely filled with water and through which cooling water circulates constantly when the piston is in operation.

Other objects and desirable features of my invention will be hereinafter pointed out.

40 Figure 1 of the drawings is a vertical sectional view of a water-cooled piston constructed in accordance with my invention, that is adapted for use with any kind of an engine or machine in which it is essential or 45 desirable to have cooling water circulate through the piston while it is in operation. Fig. 2 is an enlarged vertical sectional view illustrating a portion of one of the extensible conduits that forms part of my im- 50 proved water-cooled piston. Fig. 3 is an enlarged horizontal sectional view taken on the line 3-3 of Fig. 1.

My invention, briefly described, consists in a piston provided with a water space or 55 chamber that communicates with extensible

inlet and outlet conduits, each of which consists of coöperating tubular-shaped members arranged in telescopic relation and constructed in such a manner that there is no liability of water escaping from the interior of same and entering the crank case or other part of the engine that contains the lubricating oil.

In the preferred form of my invention as herein illustrated the tubular-shaped member that is carried by the piston passes through a stuffing box in a stationary tubular-shaped member that contains water, and a casing is provided for said stationary member so as to receive and collect any water that leaks through said stuffing box after the packing of same has become worn. The condition of said casing, namely, whether or not it contains water, can be ascertained at any time by the operator in charge of the engine by a suitable means provided for this purpose, and means are preferably provided for enabling the operator to tighten said stuffing box when a leak develops in same. I do not wish it to be understood, however, that my invention is limited to a water-cooled piston in which the members constituting the extensible water conduits are arranged in the manner just described, for the same results could be accomplished in various other ways without departing from the spirit of my invention.

Referring to the drawings which illustrate the preferred form of my invention, A designates a trunk type piston that is provided adjacent its upper end with a water space or chamber 1 through which cooling water circulates when the piston is in operation. The cooling water is supplied to said water space and conducted away from same by 95 means of two extensible conduits, each of which is preferably formed by a tubular-shaped member 2 carried by the piston and a stationary coöperating tubular-shaped member 3 provided at its upper end with a stuffing box 4 through which the tube 2 on the piston slides. The tubes 2 are screwed into the piston and each tube is preferably provided below its screw-threaded portion with a relatively large fillet 2^a so that the 100 cross-sectional area of the tube will be relatively great at the surface line of the piston and then diminish gradually from this point. By forming the tube in this manner I cause the stresses to be distributed over a 110

considerable length of the tube and thus reduce the tendency of the tube to crystallize at the surface line of the piston, due to excessive vibration. Cooling water is supplied to one of said conduits, which I will term the supply conduit, and which is shown in section in Fig. 1, by means of a supply pipe 5 and is conducted away from the discharge conduit that is shown in elevation in Fig. 1 by means of a waste pipe 6. Each conduit is provided with a casing 7 that surrounds the stationary tubular-shaped member 3 of same so as to receive and collect any water that leaks through the stuffing box 4 when the packing of same becomes worn, said casing 7 being conveniently formed by a piece of tubing whose lower end is connected to a cup-shaped casting 8 that sustains the tubular-shaped member 3, and into which the supply pipe 5 leads, as shown clearly in Fig. 1. The upper end of the casing 7 is preferably closed by a cap 7^a provided with a stuffing box 9 through which the tubular-shaped member 2 on the piston slides so as to eliminate any possibility of water escaping from the interior of the conduit into the crank case of the engine in which the casing 7 is arranged, the packing of the stuffing box 9 operating to wipe off any moisture on the movable tube 2 which might possibly leak through the stuffing box 4 and which forms a closure for the stationary tubular-shaped member 3 which is partly filled with water.

In order that a leak in the stuffing box will be made known to the operator in charge of the engine I have provided the casing 7 with a means whereby the operator can determine the condition of said casing at any time when the piston is in operation. In the embodiment of my invention herein shown said means consists of a discharge opening 10 in the lower end of the casing 7, through which water can escape into a pan 11 and drain out of said pan into a waste pipe 11^a, as shown in Figs. 1 and 3. This is only one of numerous means that may be used to notify the operator when a leak develops in the conduit, and therefore I do not wish it to be understood that my invention is limited to the means herein illustrated that is used for this purpose. If a leak develops in either of the stuffing boxes 4 or 9 the gland nuts of said stuffing boxes can be tightened from the exterior of the engine, even while the engine is in operation, by means of a rotatable sleeve 12 arranged between the stationary tubular-shaped member 3 and the casing 7 and provided at its upper end with a cap 12^a that has holes 12^b in same, as shown in Fig. 2, that are adapted to receive lugs or projections 13 on the gland nuts of the stuffing boxes 4 and 9. The sleeve 12

can be slid upwardly or downwardly so as to cause the cap 12^a at the upper end of same to engage the gland nut of either of the stuffing boxes, and after said gland nut has been engaged the sleeve can be rotated so as to compress the packing in the stuffing box and thus take up the wear on same. Various means may be employed for actuating the sleeve 12, the means herein shown consisting of a pin or bar 14 shown in broken lines in Fig. 3 that is adapted to be inserted in one of a plurality of holes 15 formed in the collar 16 at the lower end of the sleeve, as shown in Fig. 1. While the sleeve 12 above described forms a convenient means for enabling the stuffing boxes 4 and 9 to be tightened from a point outside of the crank case of the engine, and while the piston is in operation, it will be obvious that various other means could be used for this purpose without departing from the spirit of my invention.

In order that the water space or chamber 1 of the piston will remain filled with cooling water, I have provided the discharge pipe 6 with a relief valve or pressure regulator 6^a which is set to overcome either the static head or the pressure due to momentum of the water, said relief valve 6^a opening automatically at each stroke or impulse of the pump which forces the cooling water through the supply pipe 5 so as to cause the water to circulate continually through the water space 1 of the piston, but at the same time keeping said water space constantly filled with water, the supply pipe 5 being provided with a check valve 5^a, as shown in Fig. 1, so as to prevent the heated water from backing up in same during the down stroke of the piston A.

The space in the interior of the stationary tube 3 constitutes a high pressure chamber in which a relatively great pressure is created by the movement of the tube 2 on the downward stroke of the piston A, and in order to relieve or reduce the pressure in this chamber, I have provided each of the conduits with an air chamber 17, shown in full lines in Fig. 1 and in section in Fig. 3, whose upper end is closed and whose lower end communicates with the interior of the stationary tubular-shaped member 3. By constructing the conduits in this manner I reduce to a minimum the liability of water leaking through the high pressure packings 4 when the piston is operated at a high speed and provided with pipes or conduits of relatively small cross-sectional area for conducting the water into and out of the water space in the piston.

In a water-cooled piston of the construction above described it is impossible for water to escape from the conduits through which the water is supplied to and con-

ducted away from the piston, owing to the fact that each of said conduits comprises a casing or chamber that receives and collects any water which leaks through the stuffing 5 boxes 4 in which the tubular-shaped members 2 on the piston slide. Consequently, there is no liability of the cooling water entering the crank case or other part of the engine that contains the lubricating oil, thus 10 impairing the efficiency of the oil. While the low pressure stuffing boxes 9 in the tops of the casings 7 or low pressure chambers are not essential to the successful operation of my improved piston, still, I prefer to use 15 them so as to absolutely prevent any possibility of water escaping from the conduits and entering the crank case. The stuffing boxes of each conduit can be tightened conveniently from a point outside of the engine, 20 even while the engine is in operation, and as means are employed for notifying the operator when either of the stuffing boxes 4 starts to leak, the leak can be stopped before the packing becomes excessively worn. The air 25 chambers 17 are not essential, but, as previously stated, they relieve the pressure on the packing of the stuffing boxes 4, and thus reduce the liability of water leaking through said stuffing boxes.

30 Having thus described my invention, what I claim, and desire to secure by Letters Patent, is:

1. A water-cooled piston provided with an extensible conduit formed by coöperating 35 members, one of which slides within the other, the outer member being provided with an expansion chamber, and means for receiving and collecting any water that leaks through the joint between said members.

40 2. In a water-cooled piston provided with a water space, the combination of a stationary high pressure chamber that contains water, a tubular-shaped member on the piston communicating with the water space in same and projecting into said high pressure 45 chamber, and means for collecting any water that escapes from said high pressure chamber through the opening in same in which said tubular-shaped member recipro- 50 cates.

3. In a water cooled piston, the combination of a high pressure chamber that contains water, a tubular-shaped member on the piston that reciprocates in said high 55 pressure chamber, a low pressure chamber surrounding the high pressure chamber and provided with means for wiping off any water that adheres to the outer surface of the tubular-shaped member on the piston 60 when said member withdraws from the high pressure chamber, and a drain device open to the atmosphere and leading away from said low pressure chamber.

4. A water-cooled piston provided with 65 an extensible conduit formed by a tubular-

shaped member on the piston that projects through a stuffing box into a high pressure chamber that contains water, and a low pressure chamber surrounding said high pressure chamber and provided with a stuffing 70 box through which the tubular-shaped member on the piston passes.

5. In a water-cooled piston, the combination of a high pressure chamber that contains water, a tubular-shaped member on the piston that reciprocates in said high pressure chamber, a low pressure chamber surrounding the high pressure chamber for collecting water that escapes through the opening in said chamber in which said tubular-shaped member reciprocates, said low pressure chamber having a drain outlet, and means for enabling the operator in charge 75 of the apparatus to observe the rate of flow of the water that drains from said low pressure chamber.

6. In an engine, the combination of a water-cooled, trunk-type piston provided with an extensible water conduit that comprises a stuffing box, and a means projecting 90 into the piston and forming a permanent part of the engine for turning the gland nut of the stuffing box so as to tighten same, said means being capable of being operated when the piston is operating.

7. In an engine, the combination of a water-cooled piston provided with an extensible water conduit that comprises a stuffing box, and means forming a permanent part 100 of the engine and operable from the exterior of the engine for turning the gland nut of the stuffing box so as to tighten same.

8. In a machine of the character described, the combination of a water-cooled piston provided with an extensible conduit 105 formed from a tubular-shaped member on the piston that projects through a stuffing box in a coöperating tubular-shaped member, and means forming a permanent part 110 of the machine and operable from the exterior of the cylinder that receives the piston for tightening the gland nut of the stuffing box without dismantling or removing any parts of the machine.

9. A water-cooled piston provided with an extensible conduit formed by a stationary tubular-shaped member that projects upwardly into the piston and which is provided at its upper end with a stuffing box in which a coöperating tubular-shaped member on the piston slides, and a device operable from the lower end of said stationary member for tightening the gland nut of said stuffing box.

10. A water-cooled piston provided with an extensible water conduit formed by a stationary tubular-shaped member that projects upwardly into the piston and which is provided at its upper end with a stuffing box that receives a coöperating tubular-shaped member on the piston, a casing sur- 125 130

rounding said stationary member and provided with a stuffing box through which the tubular-shaped member on the piston passes, and means for enabling the gland nuts of either of said stuffing boxes to be tightened without dismantling or taking apart any of the elements of the structure.

11. A water-cooled piston provided with an extensible water conduit formed by a stationary tubular-shaped member that projects upwardly into the piston and which is provided at its upper end with a stuffing box that receives a coöperating tubular-shaped member on the piston, a casing surrounding said stationary member and provided with a stuffing box through which the tubular-shaped member on the piston passes, and a sleeve arranged inside of said casing and provided with means for engaging the gland nuts of either of said stuffing boxes so as to tighten them.

12. A water-cooled piston provided with an extensible water conduit that comprises a tubular-shaped member on the piston which reciprocates in a closed chamber that contains water, and means for relieving the excessive pressure that is created in said chamber by the displacement stroke of the tubular-shaped member on the piston.

13. A water-cooled piston provided with an extensible water conduit that comprises a tubular-shaped member on the piston, and a high pressure chamber in which said member reciprocates, said high pressure chamber containing water, and an air chamber communicating with said high pressure chamber for relieving the excessive pressure that is

created in same when the piston moves in one direction.

14. A water-cooled piston provided with a depending tubular-shaped member that reciprocates in a high pressure chamber that contains water, an air chamber that communicates with said high pressure chamber and which relieves the excessive pressure created in same when the piston moves in one direction, and a low pressure chamber for receiving and collecting the water that leaks out of said high pressure chamber.

15. A piston provided with a water space, a water supply conduit and a discharge conduit communicating with said space, and a relief valve in said discharge conduit that insures said water space remaining completely filled with water when the piston is in operation without subjecting the parts to excessive pressure during certain periods in the cycle of operations of the piston.

16. A piston provided with a water space to which water is supplied continually, a discharge conduit leading from said water space, and a relief valve in said discharge conduit that insures said water space remaining completely filled with water, but which operates automatically to prevent existence of excessive pressure within said conduits or related spaces.

In testimony whereof I hereunto affix my signature in the presence of two witnesses, this second day of January 1915.
